UNITED STATES PATENT OFFICE.

RUDOLF E. HELLMUND, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRICAL SYSTEM.

1,300,388.

Specification of Letters Patent. Patented Apr. 15, 1919.

Application filed March 4, 1915. Serial No. 12,068.

To all whom it may concern:

Be it known that I, RUDOLF E. HELLMUND, a subject of the German Empire, and a resident of Pittsburgh, in the county of Allegheny and State of Pennsylvania, have invented a new and useful Improvement in Electrical Systems, of which the following is a specification.

My invention relates to electrical systems, and it has special reference to systems of control for alternating-current railway electrifications of a certain type.

One of the objects of my invention is to provide a system of the above-indicated character which shall be adapted to prevent, automatically or otherwise, as desired, the total power absorbed by an alternating-current railway system from exceeding a certain specified maximum at any time, without, however, interfering undesirably with the operation of the several trains in operation during the period of incipient overload.

A further object of my invention is to provide a system in which, by varying the frequency of the output of a generator in a sub-station, the power input thereto may be satisfactory and may be efficiently controlled, on the one hand, and a railway system that is fed from the station may have its power demands desirably supplied at all times, on the other hand.

Another object of my invention is to provide apparatus of the class under consideration which shall efficiently, conveniently and reliably perform the intended functions at a comparatively small expense.

It is sometimes desirable, or even necessary, particularly in a case where a railway system purchases its power from an outside power company, that a predetermined maximum consumption of power shall never be exceeded, even under unusually severe operating conditions. It is especially toward means for preventing such an objectionable occurrence that my invention is directed; for, although, with an ideal distribution of trains, the power consumption may be kept within the specified limit, it is evident that such an ideal condition cannot possibly be maintained for any length of time.

In a certain railway electrification, let it be assumed that the general layout is as follows:

At various sub-stations along the railway line, three-phase 60-cycle power, supplied by an outside company, is transformed, by means of suitable frequency-changing sets, to single-phase 25-cycle energy which, as is well known, is better adapted for the propulsion of railway vehicles. Any suitable arrangement of power circuits and locomotives may be employed.

In order to meet the imposed condition of no excessive draft of power from the 60-cycle transmission mains, I have devised several relatively simple systems for performing the desired functions inexpensively, effectively and reliably. The following theoretical discussion will serve to render my invention more clearly understood.

The above-mentioned locomotives may operate on any frequency within a given range, provided the voltage varies in proportion to the frequency. For example, if the frequency should drop from the assumed normal value of 25 cycles to 20 or 15 cycles, and if the volts should decrease in the same proportion, the locomotive would operate under practically the same tractive effort as before and with the same current supplied to the motors, but the input to the locomotive would be reduced practically in proportion to the frequency and voltage. Consequently in the event of an overload on the railway system, if the frequency delivered by the sub-station should be lowered, the railway load might be reduced also. In this way, the power consumption from a transmission circuit might be kept within a specified maximum, but the train operation would be sacrificed. In other words, whereas the specified power consumption from the transmission circuit would not be exceeded, the overload current demanded by the trains in order to maintain desirable operating conditions would not be supplied and the railway service would suffer in consequence.

However, if the output of the frequency changer can be reduced in smaller proportion than the decrease in frequency and voltage or can be maintained substantially constant during such decrease, then the demanded overload current may be supplied to the railway system without exceeding the specified power consumption from the transmission line and with good train operation.

For instance, if the output of the frequency changer can be held substantially constant while the frequency and voltage are decreased 30%, then the current delivered to the locomotives and their tractive effort can be increased approximately in proportion. Thus, with such a system, by varying the frequency but not varying the output in the same proportion, it becomes possible to haul 10 heavier trains, or more of them, under over-load conditions without exceeding the predetermined power input and, in addition, without sacrificing good train operation. Whereas, a system of this type is especially 15 adapted for use with locomotives embodying induction driving motors, it will be understood that the current regulation itself does not depend upon the use of such motors, and other systems employing such 20 locomotives in part or not at all may also secure a certain degree of benefit from the system.

In a co-pending application of Benjamin G. Lamme and Francis H. Shepard, Serial 25 No. 808,716, filed December 26, 1913, and assigned to the Westinghouse Electric & Manufacturing Company, is shown and described a system of the type under consideration, wherein the speed of the driving induction motor is varied, in accordance with load conditions, to permit of a corresponding variation of the delivered frequency and current from the generator that supplies energy to the railway line, whereby the desired results may be secured.

According to my present invention, I provide means for meeting the condition above referred to, comprising a system wherein the generated frequency and current may be 40 varied, as desired, without changing the speed of the driving induction motor. One such system may include, in addition to a driving induction motor and a driven alternating-current generator, an auxiliary motor-generator set, the motor being adapted to be 45 varied in speed in accordance with load conditions of the induction motor, and the generator being adapted to regulate the frequency of the main generator. The regulating action is preferably made automatic, 50 as hereinafter set forth.

In the accompanying drawings Figures 1 and 3 are diagrammatic views of complete systems of control embodying my invention 55 and Figs. 2 and 4 are diagrammatic views of modifications of certain portions of the respective systems shown in Figs. 1 and 3.

Referring to Fig. 1, the system here shown comprises a suitable three-phase supply circuit having phase conductors A, B and C; a receiving circuit, such as an electric railway system, having supply conductors D and E, a driving induction motor IM that is fed from the three-phase supply circuit, a 60 driven single-phase generator G for deliv-

ering energy to the receiving circuit DE, and an auxiliary motor-generator set comprising a driving motor AM and an exciting generator EG, a potential transformer T that is interposed between the exciting generator EG and the main generator G, a resistor R that is arranged for three-phase operation in connection with the auxiliary driving motor AM, and a switching device SR for manipulating the resistor R in accordance with the current supplied to the motor IM.

The induction motor IM comprises a suitable stator winding 1 that may be connected to the three-phase supply circuit in any well-known manner, and, preferably, a wound rotor 2. The main generator G may be mechanically connected to the induction motor in any suitable manner, as by a shaft 3, and comprises an armature 4 of the commutator type, an induced or cross-field magnet winding F that is connected to the supply circuit DE and is inductively related to the armature 4, a plurality of short-circuited working current brushes 5, and a plurality 90 of exciting brushes 6 that are disposed in quadrature relation to the brushes 5 and are connected to the primary winding P of the transformer T.

It will be understood that the generator G is not necessarily of the type herein illustrated, but may be of other forms, as elsewhere shown. Instead of the generator being excited from its armature, as illustrated, the field winding may be disposed on the 100 stator to perform the same function. The armature excitation, however, has the advantage that the apparent energy, that is, the value of volt-amperes, supplied by the exciting generator is but little in excess of 105 the amount needed to overcome the resistance drop of the exciting current in the armature.

The auxiliary driving motor AM is here shown as being of the induction-motor type, 110 comprising a primary stator winding 7 that is connected, by a plurality of conductors 8, to the three-phase supply circuit; and a secondary rotor winding 9 that is connected, through a plurality of conductors 10, to the 115 various sections of the three-phase resistor R.

The exciting generator EG may comprise a stationary single-phase generating winding 11 that is connected to the secondary 120 winding S of the transformer T and a direct-current-excited rotatable field-magnet structure 12 that may be connected to the auxiliary driving motor AM by means of a suitable shaft 13. It will be appreciated 125 that the auxiliary motor-generator set will be called upon to deliver only a relatively small percentage of the total volt-amperes delivered to or from the main motor-generator set, inasmuch as the greater portion of the 130

voltage producing the exciting current for the armature is supplied by itself. Consequently, the capacity of the auxiliary motor-generator set and the operating losses in the resistor R will be particularly small, as compared with the energy delivered to the receiving circuit DE.

The movable member 14 of the resistor R may be connected to a suitable rotatable rod 10 or shaft 14_a, to the free end of which a link member 15 is rigidly secured. A movable core member 16 is suitably mechanically connected to the link member 15 and is adapted to be acted upon by a solenoid 17 that is 15 series-connected in one of the phase conductors A of the three-phase supply circuit.

Assuming the various machines illustrated to be normally operating and the movable member 14 of the resistor R to occupy the 20 position shown, the operation of the system may be described as follows: If the energy input to the induction motor IM attains a predetermined relatively high value, to which the current in the energizing coil 17 25 of the switching device SR is substantially proportional, since the voltage of the three-phase circuit will normally remain practically constant, the coil 17 will actuate the core member 16 to move the movable member 30 14 of the resistor R in a clockwise direction to insert a greater amount of resistance in the circuit of the secondary winding 9 of the auxiliary driving motor AM. The core member 16 and the switching device SR may 35 be returned to initial position by means of a spring 16_a. The speed of the auxiliary motor-generator set will, consequently, be reduced, and a corresponding decrease in the frequency delivered by the exciting generator 40 EG will obtain. As a result, the exciting frequency of the main generator G, and, therefore, the frequency delivered to the receiving circuit DE, will be correspondingly decreased. However, the total output of the 45 main generator G will remain substantially constant, whereby a materially increased amount of current may be derived from the receiving circuit DE without exceeding the predetermined desired maximum energy in- 50 put to the driving induction motor IM from the three-phase supply circuit A, B, C, as hereinbefore explained.

Reference may now be had to Fig. 2. The modified portion of the system illustrated 55 comprises the exciting generator EG; the potential transformer T; a synchronous motor SM of the familiar "rotating-field" type, having its armature 1 directly connected to the three-phase supply-circuit and having 60 the field-magnets of its rotor 2^a excited in any suitable manner (not shown); and a main generator G1 for delivering energy to the single-phase receiving circuit DE. This 65 type of generator is preferably employed when its speed is above the corresponding

synchronous speed and is of the double-feeding type, comprising a commutator-type armature 18, a main or exciting field-magnet winding F1 and an auxiliary or compensating field magnet winding C1. The commutator cylinder of the armature 18 is provided with a pair of supply-circuit brushes 19, one of which is connected by a conductor 20 to one end of the transformer primary winding P. The other brush 19 is connected, 75 through the field-magnet winding C1, to the other end of the winding P.

Another conductor 21 serves to connect an intermediate point 22 of the primary winding P to a point 23 that lies between the 80 field-magnet winding C1 and the armature, thus providing the well-known "double-fed" connection. The exciting field winding F1 is connected to the terminals of the generating winding 11 of the exciting generator 85 EG, while the secondary winding S of the transformer T is directly connected to the receiving circuit DE. Whereas Fig. 2 shows the exciting field winding F1 disposed on the stator of the generator G1, armature excitation, as illustrated in Fig. 1, may be employed, as desired.

It will be understood that the auxiliary driving motor AM and its accessories are connected to the system shown in Fig. 2 in 95 a manner similar to that illustrated in Fig. 1, and that the operation of the system corresponds exactly to the operation described in connection with the preceding figure; such being the case, no further exposition is 100 deemed necessary here. Inasmuch as, according to my invention, it is not necessary to vary the driving motor speed to effect a change in generator frequency, a synchronous or constant-speed driving motor may 105 satisfactorily be employed in place of an induction motor, as illustrated in Fig. 2. Consequently, a saving in first cost of installation may be effected, and moreover, if desired, power-factor correction in the poly- 110 phase supply circuit may readily be accomplished by the familiar method of varying the direct-current excitation of the synchronous motor.

In case several main generators are connected to operate in parallel relation, they may be excited by the same exciting generator EG, or several such excitors may also be connected in parallel relation.

It should be noted that the novel features 120 of the generators G and G1 are preferred, but not absolutely essential, parts of my invention, and that various types of generators may be employed; and such features are fully set forth and claimed in my co-pending application, Serial No. 23,361, filed April 23, 1915.

Referring now to Fig. 3, the system shown 130 comprises the three-phase supply circuit A, B, C; the induction motor IM; a driven

polyphase main generator G2 that is adapted to deliver energy to a three-phase receiving circuit having phase-conductors J, K and L; an auxiliary motor-generator set comprising a driving motor AM1 and an exciting generator EG1; and a switching device SR1 that is associated with the auxiliary motor AM1, in a manner to be set forth.

The main generator G2 is of the well-known asynchronous type comprising a three-phase alternating-current generating stator winding 25 and a three-phase-wound rotor 26 that may be connected to the induction motor by means of the shaft 3.

The auxiliary driving motor AM1 is of the three-phase commutator type comprising an armature 27 that is mechanically connected to the exciting generator EG1 by the shaft 13 and a three-part field-magnet winding 28. Each part of the field winding is connected to a corresponding brush member 29 of the armature 27, the brushes in this case being disposed approximately 120° apart on the commutator cylinder of the machine.

The switching device SR1 comprises a movable insulating member 30 that is provided with a plurality of suitable conducting members 31 which are severally variably connected by suitable contact fingers 32 to a plurality of taps of the field-magnet-winding portions 28, thus providing varying amounts of field-magnet windings in circuit, in accordance with load conditions of the driving induction motor IM, as about to be described. The several contact fingers 32 are connected, through a plurality of conductors 33, to the corresponding conductors of the three-phase supply circuit.

A movable core member 34 is suitably associated with the movable insulating member 30 of the switching device SR1 and is adapted to be acted upon by a solenoid 35 that is series-connected in one of the phase-conductors A of the three-phase supply circuit.

The exciting generator EG1 comprises a suitable three-phase commutator-type armature 36 and a distributed exciting field-magnet winding F2. The armature 36 is provided with a plurality of brushes 37 that are severally connected by conductors 38 to equally-spaced points 39 of the field winding F2 which are non-corresponding, that is, they are not located on the same radial lines with the brushes 37, in accordance with a familiar practice, to insure effective operation of the exciting generator EG1 with respect to the main generator G2. The points 39 are severally connected to the 120° points of the rotor winding 26 by conductors 40.

Assuming the various machines illustrated to be normally operating and the switching device SR1 to occupy the position shown,

the operation of the system may be briefly set forth as follows:

If the energy input to the induction motor IM attains a predetermined value for which the solenoid 35 is set, the core member 34 is actuated to move the switching device in such a direction as to decrease the amount of the various portions of the field magnet windings that are in circuit. The speed of the auxiliary motor AM1 is thereby correspondingly decreased, and the delivered frequency of the exciting generator EG1 and, finally, of the main generator G2, are reduced in a proportional degree for the purpose hereinbefore described. 75

The portion of the system illustrated in Fig. 4 comprises the main generator G2 that is adapted to deliver three-phase energy to the receiving-circuit conductors J, K and L and an exciting generator EG2. 80

The exciting generator EG2 may comprise a three-phase stator winding 41 that is suitably connected to the rotor winding 26 of the main generator G2 by conductors 42 and a rotor 43 that is preferably of the direct-current-excited type, as illustrated in Fig. 1 and Fig. 2. 90

Either the auxiliary driving motor AM or AM1 may be employed to drive the exciting generator EG2 and the corresponding regulating apparatus will, of course, be employed. The general operation of the system, it is believed, will be readily understood from the similarity to the systems hereinbefore described. 100

Connections between the exciting generator EG2 and the main generator G2 may be arranged in two different ways, that is, the exciter may be connected to produce a rotating field in the generator G2 that travels in the same direction or in a direction opposite to that in which the rotatable member of the main generator moves. If this rotating field travels in the same direction, the frequency delivered to the receiving circuit will equal the sum of the frequencies corresponding to the speeds of the main generator and the exciter. On the other hand, if the field produced by the exciter in the main generator travels in the direction opposite to that of the rotation of the main generator rotor, the resultant frequency will equal the difference of the frequencies that correspond to the speeds of rotation of the two machines. In either case, however, a change in the exciter frequency by reason of the change in the auxiliary driving motor speed will effect a corresponding variation in the frequency delivered to the receiving circuit. 110

I do not wish to be restricted to the specific circuit connections or arrangement of parts herein set forth, as various modifications thereof may be made without departing from the spirit and scope of my invention. 125 130

I desire, therefore, that only such limitations shall be imposed as are indicated in the appended claims.

I claim as my invention:

5. 1. In an electrical system, the combination with a driving dynamo-electric machine and an alternating-current machine driven thereby, of automatic means for varying the delivered frequency of the driven machine 10 in accordance with the current supplied to the dynamo-electric machine while maintaining the speed thereof substantially constant. 70
15. 2. In an electrical system, the combination with a driving dynamo-electric machine and an alternating-current machine driven thereby, of means for automatically varying the delivered frequency of the driven machine 20 in accordance with predetermined conditions of the driving machine while maintaining the speed thereof substantially constant. 75
25. 3. In an electrical system, the combination with a driving dynamo-electric machine and an alternating-current machine driven thereby, of means for automatically varying the delivered frequency of the driven machine 30 in accordance with the load conditions of said driving machine while maintaining the speed of said machine substantially constant. 80
35. 4. In an electrical system, the combination with a driving dynamo-electric machine and an alternating-current machine driven thereby, of dynamo-electric means influenced in accordance with the load conditions of said driving machine for varying the delivered frequency of the driven machine in accordance with said load conditions while maintaining the speed of said machines substantially constant. 85
40. 5. In an electrical system, the combination with a driving dynamo-electric machine and an alternating-current machine driven thereby, of an auxiliary motor, speed-controlling means therefor influenced directly in accordance with load conditions of said driving machine, said means being independent of the speed of the dynamo-electric machine, and an auxiliary generator driven by said 50 motor and adapted to deliver current to said first driven machine for varying the delivered frequency thereof in accordance with said load conditions, while maintaining the speed of said first driving and driven machines substantially constant. 90
45. 6. In an electrical system, the combination with a main electric motor, and an alternating-current generator driven thereby, of an auxiliary alternating-current motor, speed- 55 controlling means therefor actuated in accordance with load conditions of said electric motor and independent of the speed of said main motor, and an auxiliary-current generator driven by said auxiliary motor to deliver an exciting current to said first genera- 100
- tor for automatically varying the delivered frequency thereof in accordance with said load conditions, while maintaining the speed of said electric motor and its driven generator substantially constant. 105
7. In an electrical system, the combination with a driving dynamo-electric machine and an alternating-current machine driven thereby, of automatic means for obtaining a variation in the current frequency of the output of said driven machine while maintaining the current frequency of the input to said driving machine substantially constant and while also maintaining a substantially constant speed of said machines. 110
8. In an electrical system, the combination with a driving dynamo-electric machine and an alternating-current machine driven thereby, of automatic means for varying the delivered frequency of said driven machine in accordance with the load on the system to obtain variations in the current output thereof while maintaining a substantially constant speed and to obtain variations in said current output that are relatively disproportionate to corresponding variations in the current input to said driving machine. 115
9. In an electrical system, the combination with an alternating-current motor and an alternating-current generator driven thereby, of means comprising a dynamo-electric machine for varying the delivered frequency of said generator in accordance with load conditions of said alternating-current motor to obtain variation of the current output thereof while maintaining a substantially constant speed and to obtain variations in said current output that are relatively disproportionate to the corresponding variations in the current input to said alternating-current motor. 120
10. In an electrical system, the combination with a driving dynamo-electric machine and an alternating-current machine driven thereby, of means automatically controlled by the current supplied to the driving machine for delivering a current of variable frequency to the driven machine to vary the frequency of the generated current thereof while maintaining its speed substantially constant. 125
11. In an electrical system, the combination with a driving dynamo-electric machine and an alternating-current generator driven thereby, of means for automatically delivering a current of variable frequency to said generator in accordance with the load conditions of said driving machine to vary the generated current frequency of the generator while maintaining the speed thereof substantially constant. 130
12. In an electrical system, the combination with an alternating-current motor and an alternating-current generator driven thereby, of means comprising a dynamo-

- electric machine for automatically delivering a current of variable frequency to said generator in accordance with the load conditions of said motor to vary the generated current frequency of the generator while maintaining the speed thereof substantially constant. 45
13. In an electrical system, the combination with an alternating-current motor, and 10 a main alternating-current generator driven thereby, of an auxiliary motor-generator set adapted to deliver energy to said generator to effect a change in the frequency of the current generated thereby and means for 15 varying the speed of said set in accordance with the load conditions of said alternating-current motor, said main generator being adapted for armature excitation, whereby 20 said motor-generator set may be of relatively small capacity. 50
14. In an electrical system, the combination with a substantially constant-speed main motor, and a main alternating-current generator driven thereby, of an auxiliary 25 motor having a speed-controlling winding, a variable resistor connected in circuit with said winding, means for varying said resistor in accordance with load conditions of said main motor, and an auxiliary alternating- 30 current generator driven by said auxiliary motor to deliver a current to the main generator to effect a change in the frequency thereof, said main generator being adapted for self-excitation, whereby the auxiliary 35 motor and auxiliary generator may be of relatively small capacity. 55
15. In an electrical system, the combination with a source of energy, a driving dynamo-electric machine connected to said 40 source and an alternating-current generator driven by said machine, of means comprising a dynamo-electric machine for delivering a current to said alternating-current generator to regulate the frequency of the 45 current generated thereby, and means independent of the speed of said driving machine for governing the speed of the last-named dynamo-electric machine in accordance with the load on the first-named dynamo-electric machine. 60
16. In an electrical system, the combination with a source of energy, a driving motor connected to said source and a main generator driven by said motor, of means comprising a motor-generator set directly connected to said source of energy for governing the frequency of the current generated by said main generator and automatic means controlled in accordance with the load on said driving motor for governing the speed 65 of said motor-generator set. 65
17. In an electrical system, the combination with a source of energy, a driving motor connected to said source of energy and a main generator driven by said motor, of means comprising a dynamo-electric machine directly connected to said source of energy for energizing said main generator to govern the frequency of the current produced thereby, and means for governing the speed of said dynamo-electric machine in accordance with the load on said driving motor. 70
18. In an electrical system, the combination with a set comprising a driving dynamo-electric machine and an alternating-current machine driven thereby, of means independent of the speed of said set for automatically varying the delivered frequency of the driven machine in accordance with 75 the load conditions of said set. 75

In testimony whereof I have hereunto
subscribed my name this 18th day of Feb.
1915.
